MAGNETIC FLY-WHEEL.

1,263,694.

Specification of Letters Patent. Patented Apr. 23, 1918.

Application filed March 1, 1915. Serial No. 11,431.

To all whom it may concern:

Be it known that we, CHRISTOPHER J. MEYER and EUGENE P. GLEASON, citizens of the United States, residing at Milwaukee, county of Milwaukee, and State of Wisconsin, have invented new and useful Improvements in Magnetic Fly-Wheels, of which the following is a specification.

Our invention relates to improvements in magnetic fly wheels with particular reference to that class of fly wheels which serve the double purpose of a fly wheel and a rotary field magnet for a magneto generator inclosed wholly or partially within the fly wheel rim.

The object of our invention is to provide a simple and inexpensive form of magnetic fly wheel, which can be manufactured in large numbers on short notice and which will be particularly suited to the demands of small fly wheel magneto generators.

The accompanying drawing shows our improved magnetic fly wheel in perspective with one side partially broken away to show a portion of the web and one of the magnets in section.

A disk A of non-magnetizable material is provided with a central aperture B to receive a shaft, this being surrounded by a circular row of bolt apertures C to facilitate bolting the fly wheel to a hub or supporting member. The outer marginal portions of the disk are pressed and partially folded to form a rim D, the extreme edge margin being turned inwardly to form an inwardly projecting circular flange E at the side of the rim D farthest from the body of the disk A. A set of segmental magnetic bars F, F', are inclosed within the rim D between the inturned marginal flange E and the disk A, the ends of these magnetic bars being brought into close proximity at f, f'. They may, if desired, be separated from each other by an air gap or any other suitable insulating material, although this is not essential.

Pole pieces G, G' span the abutting ends of the magnet bars F, F', and are secured thereto and to the rim D by bolts or rivets H.

The fly wheel above described may be

constructed by placing the magnetic segments upon a flat disk of non-magnetizable material of greater diameter than the ring formed by the segment, the outer portions 55 of said disk being thereupon folded in a suitable press over the magnetic ring, thus forming the rim D and inturned flange E. The magnetic ring segments will thus be secured in position and the pole pieces can 60 be subsequently attached.

If desired, the disk A may be first inserted in a press to form the annular fold or elbow at d, thus producing a shallow cup or basin into which the magnetic segment bars may 65 be placed and the margins of the basin subsequently folded inwardly to form the flange E. It will be observed that the mass of material, which stores the momentum energy 70 of the fly wheel, will be principally furnished by the magnet bars and pole pieces, which may be made of any desired weight. The web and rim of the wheel may therefore be composed of comparatively light material, which may easily be bent or pressed into 75 the desired shape, and large numbers of these may be quickly formed by employing an ordinary stamping press and suitable dies.

We claim—

A magnetic fly wheel, comprising a disk of non-magnetic sheet metal having its marginal portion extended laterally to form a cylindrical rim, the free margin of said rim being curved inwardly and constituting 85 a rounded bead flange, in combination with a set of segmental magnet bars arranged end to end in circular form and inclosed by the rim and frictionally engaged by the free edge of the bead flange to oppose rotation 90 within the rim, pole pieces at the ends of the magnet bars, and connecting members extending through the pole pieces, segmental magnet bars, and rim.

In testimony whereof we affix our signatures in the presence of two witnesses.

CHRISTOPHER J. MEYER.
EUGENE P. GLEASON.
